UNITED STATES PATENT OFFICE.

SYLVESTER L. GOOKIN, OF QUINCY, MASSACHUSETTS, ASSIGNOR TO UNITED SHOE MACHINERY CORPORATION, OF PATERSON, NEW JERSEY, A CORPORATION OF NEW JERSEY.

FASTENER-INSERTING MACHINE.

Application filed August 26, 1924. Serial No. 734,251.

This invention relates to fastener-inserting machines. The accompanying drawings illustrate the invention as embodied in an eyeleting machine.

In the manufacture of certain articles of wearing apparel, leather goods and novelties, it is, in some cases, desired to insert one or more eyelets, while in other cases it may be desired merely to punch one or more holes without setting any eyelet. Even in the first case it is necessary to punch holes to receive the eyelets. In dealing with such articles and others in which holes are to be punched singly with or without setting eyelets it is not feasible to use eyeleting machines that include automatic punching mechanism and automatic work-feeding mechanism, since machines of that type are too large and costly and are designed to operate at high speed on work that requires a series of eyelets uniformly spaced one from another. Consequently, the manufacturers of articles of the character above mentioned have heretofore been supplied with simple and comparatively inexpensive punching machines and with separate machines having eyelet-setting mechanism but no punching mechanism or work-feeding mechanism. While this equipment of two separate machines, one for punching holes and the other for setting eyelets, requires only a relatively small investment as compared to the cost of an automatic punching and eyeleting machine, it has certain disadvantages, the elimination of which is one of the objects of the present invention.

Stated more definitely, an object of the invention is to provide an improved eyeleting machine of the simple type above referred to which may be quickly and readily converted into a machine for performing punching operations only and be just as readily when desired reconverted into an eyeleting machine. To this end, and in accordance with the present invention, the illustrated eyeleting machine, which is of a well-known foot power type, in which eyelets are supplied automatically by a raceway to one of the setting tools which is provided with a spring-pressed spindle normally projecting to pick the leading eyelet from the raceway and hold it for insertion in the work, is provided with a member, illustrated as a cap or thimble, formed to be

seated on the eyelet-setting tool to serve as a punch bed when the machine is to be used for punching operations only, together with means for maintaining the punch-bed in that position with sufficient force to keep the spring-pressed spindle depressed so that it cannot function. The illustrated cap or thimble is adapted to be attached and detached at will and besides serving as a punch-bed, when attached has the further advantage just indicated of preventing the spindle from picking eyelets from the raceway when the machine is used for performing punching operations only. Preferably, too, and as herein illustrated, the machine is provided with a combined punching and clenching tool co-operating with the spindle-carrying setting tool referred to. This avoids substituting one tool for another when it is desired to convert the machine from an eyelet-inserting machine into a simple punching machine and vice versa, such a tool being adapted either for eyeleting or for punching.

Another feature of the invention consists in a punch-bed having one or more resilient elements integral therewith and arranged to hold the punch-bed in operative position on a fastener-inserting tool without requiring the use of any tool to attach or detach it.

Although the invention is herein set forth with particular reference to eyeleting machines of a well-known type, since it was in view of problems which, as above explained, have arisen in the use of such machines that the invention was developed, it should be understood that in various aspects the invention is not restricted in its applicability to fastener-inserting machines of the illustrated type.

Referring to the drawings,

Fig. 1 is a vertical section of a portion of a well-known type of fastener-inserting machine converted into a punching machine by devices hereinafter described, and

Fig. 2 is a vertical section on a larger scale showing the punching devices in the act of punching a hole in an article of work.

So far as the fastener-inserting mechanism is illustrated herein the construction is the same as that more fully shown and described in Letters Patent of the United States No. 898,729, granted September 15, 1908, on application of John F. Davey. To

facilitate a description of the operation of the punching devices a brief preliminary description will be directed to the fastener-inserting mechanism per se.

The illustrated machine comprises a frame 10 designed to stand on a bench 12. A stationary overhanging portion 14 of the frame is bored to receive the shank 16 of a tool for clenching the fasteners, while the lower portion of the frame is bored to provide a bearing 18 for a vertically movable plunger 20 which carries a fastener-inserting tool 22. A screw 15 serves as an adjustable abutment for the shank 16 while a set-screw 17 is arranged to hold the shank. A raceway 24 for supplying eyelets is carried by two movable members one of which is indicated at 26 and is mounted to oscillate on a fulcrum pin 28. Mechanism herein-after described is provided to move the plunger 20 up and down and to oscillate the raceway carrier 26 so that the delivery end of the raceway will present the leading fastener to the fastener-inserting tool 22 while the latter is rising, and then be retracted to the left to avoid interfering with the inserting tool.

The operating mechanism is designed to be operated by a treadle (not shown) and includes a rod 30 by which the motion of the treadle is transmitted. The rod 30 is normally maintained in its upper position by a spring 32. The lower portion of the frame 10 supports the fulcrum pins 34 and 36. A lever 38 mounted on the pin 34 is connected to the treadle rod by a pivot pin 40. Toggle members 42 and 44 are connected respectively to the lever 38 and to the plunger 20 by pivot pins 46 and 48 and are connected to each other by a pivot pin 50. The pin 50 also extends through an arm 52 whose function is to guide the knee of the toggle as formed by the connection between the links 42 and 44. The arm 52 is mounted to swing on the pin 36. This train of connections furnishes all that is necessary to operate the plunger 20, but other elements are included to operate the raceway.

To utilize the toggle member 44 for the purpose of reciprocating the raceway said toggle member is formed with an arm 54 the upper end of which carries an anti-friction roll 56. The raceway carrier 26 is provided with an anti-friction roll 58 against which the roll 56 acts to retract the raceway from the path of the inserting tool, and is also provided with an anti-friction roll 60 to be engaged by a surface 62 of the arm 54 to move the delivery end of the raceway to the position shown.

The fastener-inserting tool 22 is provided, as usual, with a spindle 64 whose function is to pick the leading eyelet from the raceway and maintain the eyelet on the upper end of the inserting tool. As nearly all

constructions for operating in this manner, the spindle 64 is normally projected above the upper end of the inserting tool by a light compression spring 66 but is capable of being fully depressed into the bore of the inserting tool. 70

It has been customary to use, in machines of this type, a simple clenching tool, that is, a tool designed to perform a clenching function but no punching function. Now, for the purposes of the present invention, a punching tool is essential, and while it would be within the scope of this invention to use a simple punching tool in place of the usual clenching tool, I prefer to provide 75 a combined punching and clenching tool to avoid substituting one tool for another whenever it is desired to convert the machine from a fastener-inserting machine into a punching machine and vice versa. 80 In accordance with this preference, the illustrated construction includes a tool or anvil having an annular clenching surface 68 and a punching portion 70 projecting therefrom, said portion being tubular and its bore 85 having an outlet at one side to discharge the disks or chips punched from the work. The fastener-inserting tool 22 and the combined punch and set 70, 68 are arranged in confronting relation to each other so that they 90 may cooperate to punch holes or insert fasteners, as the case may be. When used to insert fasteners, the punching portion 70 enters the fastener and guides it to the clenching surface 68, and in that capacity 95 it is sometimes termed a pilot.

As shown best in Fig. 2, a punch-bed is provided by a plate 74 and this plate is seated on the upper end of the inserting tool 22. In this position the punch-bed engages the spindle 64 and depresses it into the tool 22 so that it is prevented from engaging the leading eyelet at the delivery end of the raceway. Thus, the mere presence of the punch-bed in its cooperative relation to the inserting tool accomplishes all that is necessary to prevent the machine from functioning as a fastener-inserting machine even though the raceway, charged 100 with fasteners, continues to move to and from its regular fastener-presenting position. The punch-bed is preferably the crown portion of a cap or thimble 76 of hardened steel or other suitable metal, and said cap or thimble is formed to fit over 105 the inserting tool so that it may be readily slipped on and removed. The sleeve portion of the thimble is preferably formed with kerfs 77 by which it is provided with resilient spring tongues 78 adapted to grip 110 the sides of the tool 22 with sufficient force to maintain the punch-bed seated upon the upper end of the tool notwithstanding the tendency of the spring 66 to separate it 115 from its seat. No tool is required to at- 120 125 130

tach or detach the member 76, since the force of the spring 66 is so slight that the gripping action of the spring tongues 78 may easily be powerful enough to hold the spindle in its fully depressed position without making it difficult to attach and detach the member 76 with the bare hand. That portion of the sleeve in which the kerfs are formed to provide the tongues 78 is pref-

erably thin for the sake of resilience, whereas the upper portion of the sleeve is relatively thick to provide an external shoulder 79 by which to detach the thimble from the tool 22. Moreover, as shown, the crown or punch-bed 74 is also substantially thicker than the tongues 78 for the sake of rigidity to counteract irregularities in the eyelet-engaging end of the tool 22.

A fastener-inserting machine equipped with a combined punching and clenching tool of the type shown may therefore be used alternatively as a fastener-inserting machine or as a simple punching machine according to whether the member 76 is detached or attached. When attached it functions first to prevent cooperation of the spindle 64 and the raceway and thereafter functions to force an article of work 80 against the punching element 70 as shown.

Having thus described my invention, what I claim as new and desire to secure by Letters Patent of the United States is:

1. A fastener-inserting machine comprising a fastener-inserting tool and a punch arranged in confronting relation to each other, said tool having a spring-pressed spindle arranged to enter the fastener, a detachable device adapted to be applied to said tool to repress said spindle and to provide a punch-bed confronting said punch, and means for relatively moving said tool and said punch to operate on an interposed article of work.

2. A fastener-inserting machine comprising a fastener-inserting tool provided with a seat for a fastener, a combined punch and set formed with a clenching surface and a punching portion projecting therefrom both arranged in confronting relation to said seat, means carried by said tool to provide a punch-bed for said punch, and means arranged to effect relative movement of said tool and said combined punch and set to punch a hole in a piece of work lying on said punch-bed.

3. An eyeleting machine comprising an eyelet-inserting tool, a carrier therefor, means for supporting an anvil in cooperative relation to said tool, two cooperative punching members one of which is fastened to said supporting means and the other of which is carried by said tool, and means for operating said carrier to cause cooperation of said punching members.

4. A fastener-inserting machine comprising a fastener-inserting tool having a central spring-pressed fastener-engaging spindle, a punch, a punch-bed adapted to be seated on the fastener-engaging end of said tool and formed to cover said spindle, and means for detachably holding said punch-bed on said end in position to keep said spindle depressed.

5. A fastener-inserting machine comprising a fastener-inserting tool and a tubular punch arranged in cooperative relation confronting each other, a detachable one-piece element consisting of a punch-bed and means for securing it on the fastener-engaging portion of said tool in cooperative relation to said punch, and means for relatively moving said tool and said punch to cause operation of one against the other.

6. A fastener-inserting machine comprising an axially movable fastener-inserting tool, a punch, and a thimble carried by said tool, the sleeve portion of said thimble being arranged to surround said inserting tool and the crown portion thereof being formed and arranged to cover the fastener-engaging portion of said tool and to provide a punch-bed for said punch.

7. A fastener-inserting machine comprising an axially movable fastener-inserting tool, a punch, and a thimble carried by said tool, the sleeve portion of said thimble being arranged to surround said tool and having one or more resilient portions to produce a frictional holding action, the crown portion of said thimble being formed and arranged to provide a punch-bed for said punch.

8. A fastener-inserting machine comprising a fastener-inserting tool, a spring-pressed spindle carried thereby, a punch, and means carried by and detachably secured to said tool in position to hold said spindle repressed, said means including a punch-bed arranged to cooperate with said punch.

9. A fastener-inserting machine comprising an axially movable fastener-inserting tool, a punch, and a thimble carried by said tool, the sleeve portion of said thimble being arranged to surround said tool and having a telescopic fit thereon, and the crown portion of said thimble being formed and arranged to cover the fastener-engaging portion of said tool and to provide a punch-bed for said punch.

10. A fastener-inserting machine comprising two cooperative fastener-inserting tools and means for relatively moving them to insert a fastener, one of said tools having a punching portion arranged to guide the fastener, and a detachable member formed to be applied to the other one of said tools to provide a punch-bed for cooperation with said punching portion.

11. A fastener-inserting machine comprising two cooperative fastener-inserting tools and means for relatively moving them to insert a fastener, one of said tools having a spring-pressed spindle arranged to enter the fastener, and the other having a punching portion arranged to enter the fastener, and means adapted to be secured to the tool first specified to repress said spindle and to provide a punch-bed for cooperation with said punching portion.

12. In combination, an eyelet-inserting machine comprising an eyelet-inserting tool and a punch arranged in confronting relation to each other, said tool being provided with a spring-pressed spindle arranged to enter an eyelet, an attachment consisting of a thimble arranged to cap the fastener-engaging portion of said tool to repress said spindle and to provide a punch-bed for said punch, the sleeve portion of said thimble including one or more resilient elements formed to retain the thimble on said tool by friction more powerful than the spring stress applied to said spindle, and means for relatively moving said tool and said punch

to effect cooperation of said punch and said punch-bed.

13. An attachment for an eyelet-inserting tool comprising a metallic thimble the sleeve portion of which is divided by one or more kerfs to provide resilient means for gripping the sides of an eyelet-inserting tool, the crown portion of said thimble being substantially thicker than said resilient means and adapted to be seated on the eyelet-engaging seat of said tool to provide a punch-bed with which a punch may cooperate.

14. An attachment for an eyelet-inserting tool comprising a metallic thimble the crown portion of which is adapted to be seated on the eyelet-engaging seat of an eyelet-inserting tool to provide a punch-bed, the sleeve of said thimble having a relatively thick portion to provide a shoulder by which to detach the thimble from the tool, and having a relatively thin portion divided by one or more kerfs to provide resilient means for gripping the sides of said tool.

In testimony whereof I have signed my name to this specification.

SYLVESTER L. GOOKIN.
